(57) **CLAIM**

The ornamental design for a detector pen tip for collecting biological fluids, as shown and described.

DESCRIPTION

FIG. 1 is a perspective view of a first embodiment of a detector pen tip for collecting biological fluids showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of the detector pen tip for collecting biological fluids showing our new design;

FIG. 9 is a front view thereof;

FIG. 10 is a rear view thereof;

FIG. 11 is a left side view thereof;

FIG. 12 is a right side view thereof;

FIG. 13 is a top view thereof; and,
